US00D944851S

(12) **United States Design Patent** (10) **Patent No.:** **US D944,851 S**
Wu (45) **Date of Patent:** **** Mar. 1, 2022**

(54) **DISPLAY SCREEN OR PORTION THEREOF WITH GRAPHICAL USER INTERFACE**

(71) Applicant: **Kai OS Technologies (Hong Kong) Limited**, Kowloon (HK)

(72) Inventor: **Meng-Hsun Wu**, Taipei (TW)

(73) Assignee: **KAI OS TECHNOLOGIES (HONG KONG) LIMITED**, Kowloon (HK)

(**) Term: **15 Years**

(21) Appl. No.: **29/721,631**

(22) Filed: **Jan. 22, 2020**

(51) LOC (13) Cl. **14-04**

(52) U.S. Cl.

USPC **D14/488**

(58) **Field of Classification Search**

(57) **CLAIM**

The ornamental design for a display screen or portion thereof with graphical user interface, as shown and described.

DESCRIPTION

FIG. 1 is a front view of a display screen or portion thereof with graphical user interface of a first embodiment showing the claimed design;

FIG. 2 is a front view of a display screen or portion thereof with graphical user interface of a second embodiment showing the claimed design; and,

FIG. 3 is a front view of a display screen or portion thereof with graphical user interface of a third embodiment showing the claimed design.

The dashed and square-dotted broken line showing of text and graphical user interface elements form no part of the claimed design. The dot-dashed lines show a display screen or portion thereof and form no part of the claimed design.

1 Claim, 3 Drawing Sheets
